APPARATUS FOR USE IN CHEMICAL DIGESTIONS

Abraham Henwood, Cynwyd, and Raymond M. Garey, Willow Grove, Pa.

Application October 30, 1933, Serial No. 695,916

10 Claims. (Cl. 23—292)

Our invention relates to an apparatus for use in conducting chemical reactions and more particularly it relates to an apparatus for use in Kjeldahl digestions such as are employed in the quantitative determination of nitrogen, especially in organic materials.

The principal object of our invention is to provide an economical apparatus by which digestions of the Kjeldahl type may be carried out efficiently with the suppression of sulphuric acid mist and the accompanying elimination of the special fume closet, the digestion room, and the expensive and complicated systems heretofore employed.

Another object of the present invention is to furnish an apparatus for use in Kjeldahl digestions in which the escape of the mist of sulphuric acid from the flask is prevented, while permitting the steam, sulphur dioxide, and carbon dioxide formed in the process of digestion to escape freely, thereby allowing the digestion to be carried out on the laboratory table without increasing pressure within the apparatus.

Other objects will be apparent from a consideration of the specification and claims.

In the accompanying drawing:—

Figure 1 is a perspective view of the apparatus of the present invention; and

Figure 2 is an enlarged fragmentary cross sectional view of the apparatus shown in Figure 1.

As is well known, Kjeldahl digestions, as conducted heretofore, have been associated with the evolution from the digestion flask of very irritating and corrosive sulphuric acid mist which continues throughout the digestion, requiring the use of special digestion closets or special digestion rooms the atmosphere of which soon becomes contaminated with the sulphuric acid fumes. The attempts to abate this nuisance have usually been concerned with the disposal of the mist after its issuance from the digestion flask, for example by placing the mouth of the flask through a hole in a lead pipe which in turn has an exit leading outdoors. In other instances, expensive and complicated apparatus has been suggested for use. The apparatus of the present invention approaches the problem from a different standpoint and effectively prevents the escape of the sulphuric acid mist from the digestion flask. The steam, sulphur dioxide, and carbon dioxide generated, however, are evolved from the flask during the process in the same manner as usually occurs so that the pressure inside the flask is not increased. Since the sulphuric acid mist fails to find its way into the room, the digestions when conducted in the apparatus of the present invention may be performed on the open laboratory shelf without discomfort to the operator.

The apparatus of the present invention is characterized by a novel combination of the usual

Kjeldahl flask and a porous acid-resistant septum placed in the neck of the flask and fitting closely therein, the septum being characterized by its ability to permit the free passage of gases therethrough but at the same time to prevent the escape of sulphuric acid mist. The septum also effectively prevents the setting up of convection currents of gases which in the ordinary procedure permits access of cold air to the flask which chills the gas space of the flask and produces throughout this space a dense fog or mist of sulphuric acid. With the apparatus of the present invention no cold air gains admission and, therefore, the walls of the body of the flask act as a condensing surface for the sulphuric acid with no accompanying condensation in the gas space of the flask. The septum may be composed of a wide variety of materials so long as it is inert to sulphuric acid vapors, and it is preferably ceramic in nature. For example, it may be manufactured of alumina or silica grains sintered together, or a product resulting from the sintering of the grains of the oxides of the rare earth elements may be used. Preferably, the septum is in the form of an elongated hollow cylindrical member open at one end, the walls and other end of which are made of alundum (sintered alumina grains). The cylindrical member is so dimensioned with respect to the neck of the flask that it fits snugly therewithin so that the materials evolved during the digestion can only escape from the flask through the porous cylindrical member. The tube is also advantageously flanged at the top so that it may be supported on the flange of the Kjeldahl flask. If desired, although it is not necessary, a stopper and delivery tube may be inserted in the mouth of the alundum tube, thus providing a means for leading the sulphur dioxide, carbon dioxide, and steam into soda lime or other convenient absorbent.

The preferred embodiment of the invention is illustrated in the drawing where the usual Kjeldahl flask is shown at 1, with the alundum elongated hollow cylindrical member 2 fitting snugly within the neck of the flask. The lower end of the cylindrical member 2 is also made of alundum and furnishes a closure for the cylindrical member as shown at 3. The tube has a flange 4 at the top thereof which fits over the flange 5 at the neck of the flask, thus providing a support for the tube.

In Kjeldahl digestions with the apparatus of the present invention, the procedure normally followed is employed. In a typical case, the flask is charged with the weighed material to be digested. Two or three granules of porous material are placed in the flask to insure smooth boiling and ten grams of potassium sulphate and twenty cubic centimeters of concentrated sulphuric acid

- are added. The alundum elongated hollow cylindrical member is inserted in the neck of the flask and if desired the member may be taped just below the flange with a small amount of filter paper
- 5 in order to make doubly sure that the joint is tight. The flask containing the alundum hollow cylindrical member is placed in the usual position for digestion, for example at an angle in the neighborhood of 45°. Heat is supplied to the bottom of the flask by a small flame, for example three-quarters of an inch to one inch high, and the heating is continued with this flame for about fifteen minutes, during which time sulphur dioxide and carbon dioxide escape. The flame is
- 10 then raised so that the tip touches the flask and the flask is heated until the material boils gently. Steam will be evolved from the flask. When the steam has been expelled, the neck of the flask around the alundum hollow cylindrical member cools as is indicated by the absence of accumulation of water on a cold glass rod inserted in the tube. The flame is raised further and boiling continued until the material in the flask is waterwhite, indicating that the digestion is completed.
- 15 The alundum hollow cylindrical member is removed from the flask when its contents have cooled. The hollow cylindrical member is filled with water which is allowed to flow into the flask in order that any traces of spray containing ammonium sulphate will be returned to the digested fluid in the flask, thereby permitting complete recovery. The material in the flask is then diluted to the usual volume, and distillation is conducted in the usual manner.
- 20 35 The device of the present invention is simple, cleanly, convenient, inexpensive, and efficient, and permits the conduction of Kjeldahl digestions without the evolution of sulphuric acid mist from the flask. Considerable modification is possible in the construction of the septum and in the materials from which it is made without departing from the essential features of our invention.
- 40 We claim:
1. An apparatus for use in Kjeldahl digestions, comprising a Kjeldahl flask and an acid-resistant 45 septum fitting snugly within the neck of said flask to prevent the formation of sulphuric acid fog by excluding cold air from said flask, such septum being pervious to the passage of gases but impervious to the passage of sulphuric acid mist.
2. An apparatus for use in Kjeldahl digestions, comprising a Kjeldahl flask and an acid-resistant ceramic septum fitting snugly within the neck of said flask to prevent the formation of sulphuric acid fog by excluding cold air from said flask, such septum being pervious to the passage of gases but impervious to the passage of sulphuric acid mist.
3. An apparatus for use in Kjeldahl digestions, comprising a Kjeldahl flask and an acid-resistant alundum septum fitting snugly within the neck of said flask to prevent the formation of sulphuric acid fog by excluding cold air from said flask, such septum being pervious to the passage of gases but impervious to the passage of sulphuric acid mist.
4. An apparatus for use in Kjeldahl digestions, comprising a Kjeldahl flask and an acid-resistant 70 septum in the form of an elongated hollow cylindrical member open at one end fitting snugly

within the neck of said flask to prevent the formation of sulphuric acid fog by excluding cold air from said flask, said septum being pervious to the passage of gases but impervious to the passage of sulphuric acid mist.

5. An apparatus for use in Kjeldahl digestions, comprising a Kjeldahl flask and an acid-resistant ceramic septum in the form of an elongated hollow cylindrical member open at one end fitting snugly within the neck of said flask to prevent the formation of sulphuric acid fog by excluding cold air from said flask, said septum being pervious to the passage of gases but impervious to the passage of sulphuric acid mist.

6. An apparatus for use in Kjeldahl digestions, comprising a Kjeldahl flask and an acid-resistant alundum septum in the form of an elongated hollow cylindrical member open at one end fitting snugly within the neck of said flask to prevent the formation of sulphuric acid fog by excluding cold air from said flask, said septum being pervious to the passage of gases but impervious to the passage of sulphuric acid mist.

7. An apparatus for use in Kjeldahl digestions, comprising a Kjeldahl flask and an acid-resistant septum fitting snugly within the neck of said flask to prevent the formation of sulphuric acid fog by excluding cold air from said flask, said septum being in the form of an elongated hollow cylindrical member open at one end and having a flange at said open end adapted to seat on the flange of the neck of said flask and being pervious to the passage of gases but impervious to the passage of sulphuric acid mist.

8. An apparatus for use in Kjeldahl digestions, comprising a Kjeldahl flask and an acid-resistant ceramic septum fitting snugly within the neck of said flask to prevent the formation of sulphuric acid fog by excluding cold air from said flask, said septum being in the form of an elongated hollow cylindrical member open at one end and having a flange at said open end adapted to seat on the flange of the neck of said flask and being pervious to the passage of gases but impervious to the passage of sulphuric acid mist.

9. An apparatus for use in Kjeldahl digestions, comprising a Kjeldahl flask and an acid-resistant alundum septum fitting snugly within the neck of said flask to prevent the formation of sulphuric acid fog by excluding cold air from said flask, said septum being in the form of an elongated hollow cylindrical member open at one end and having a flange at said open end adapted to seat on the flange of the neck of said flask and being pervious to the passage of gases but impervious to the passage of sulphuric acid mist.

10. An apparatus for use in Kjeldahl digestions, comprising a Kjeldahl flask and an acid-resistant porous septum fitting snugly within the neck of said flask, said septum being in the form of an elongated hollow cylindrical member open at one end and having a flange at said open end adapted to seat on the flange of the neck of said flask and being pervious to the passage of gases but impervious to the passage of sulphuric acid mist and effectively preventing the setting up of convection currents of gases and the consequent influx of cold air with the formation of mist or fog in the gas space of the flask.
